APPARATUS FOR BURNING SOLID FUEL

Gunnar Ganner, Lidingo, Sweden, assignor to
Svenska Aktiebolaget Gasaccumulator, Stockholm, a corporation of Sweden

Application March 4, 1937, Serial No. 128,889
In Sweden March 7, 1936

1 Claim. (CL. 126—10)

The present invention relates to apparatus for burning solid fuel and has particular reference to apparatus for burning solid fuel continuously over long periods of time. Still more particularly, the invention relates to such apparatus for burning solid fuel in domestic heating apparatus such as cook stoves, water heaters, household boilers, and the like.

For apparatus of the above general character, much is demanded in the way of reliability of operation and ease of handling. These factors have been brought to a state of development such that ordinarily all of the attention that is required is limited to supplying the apparatus with fuel and shaking down and removing the ashes at regular intervals. The necessity for shaking down the ashes is an undesirable feature of the operation of solid fuel burning apparatus since it is practically impossible to prevent the formation of dust and dirt in the place where the apparatus is located.

The general object of the present invention is to improve apparatus of the kind above referred to and to provide novel apparatus constructed in such manner that continuous combustion may be maintained without the necessity for shaking down ashes. A further object is to provide apparatus of the character under consideration having greater reliability of operation than has heretofore been obtainable, and insuring continuity of efficient combustion.

Other and more detailed objects of the invention and the advantages to be derived from its use, will appear as this description proceeds.

In order to aid an understanding of the manner in which the objects of the invention are achieved and the relation of the novel apparatus contemplated by the invention to apparatus heretofore employed, it is desirable to first review briefly the general characteristics of the prior forms of apparatus of the character under consideration.

In prior apparatus, the grate for supporting fuel has been made with relatively large grate bar area and relatively small spaces between the grate bars, in order to prevent unconsumed pieces of fuel from falling through the grate into the ash bed. Because of this the grate bars have taken up a relatively large part of the total area of the grate. As a consequence, the grate has a relatively large heat conducting capacity, thus conducting heat away from the layer of fuel lying closest to the grate. Also, radiation of heat downwardly from the fuel bed has been screened to a large extent so that substantially no preheating of the combustion air due to heat

from the fuel bed can be obtained before the combustion air actually enters the fuel. Such prevention of downward radiation to the ash bed is usually deliberately intended, in order to avoid loss of heat to the greatest possible extent due to radiation to the ashpit.

The net result of these factors is that in the usual form of combustion apparatus the layer of fuel lying nearest to or on the grate, is chilled to an extent such that combustion in this layer is retarded or ceases to an extent producing a bed of unconsumed fuel hindering the ashes from falling through the grate. Above this lower layer there is, however, a high rate of combustion and as the conduction of heat from this layer is relatively slight, the temperature rises to such an extent that the ash sinters or fuses into slag or clinker which eventually may shut off all further supply of air to the combustion zone and thus cause the fire to go out. A further disadvantage of slag is that unconsumed fuel particles are often imbedded in the slag or clinker and shut off from combustion air so that low combustion efficiency results. Also, slag formation frequently prevents ash from being removed from the grate by ordinary shaking of the grate, requiring breaking up by the use of a slice bar before it can be removed.

In accordance with the present invention, the above described phenomena are prevented from taking place, and the resultant disadvantages avoided by regulating combustion in such a way that it will take place only in a thin layer immediately above the grate. In general it may be said that this is attained by providing apparatus which will operate to cause preheating of the air so that it will have a high temperature when striking the fuel bed and in which the minimum combustion temperature is limited to prevent it from rising to a temperature resulting in slagging or clinkering of the ash.

In order to effect this, the grate is formed and arranged in such a way that an effective radiation of heat downwardly from the fuel bed on the grate is obtained. This is done by proportioning the ratio of the spaces between the grate bars to the width of the bars so that the total portion of the grate area formed by the spaces between the grate bars is large as compared to the portion of the space occupied by the bars themselves. This general character of grate construction, combined with other features of construction, as will hereinafter be more fully pointed out, has been found to provide for a character of combustion that will reliably continue so long as

fuel and air are supplied and which will cause the ash to automatically fall through the grate without it being necessary for the grate to be shaken.

5 In the accompanying drawings forming a part of this specification, suitable apparatus for carrying the invention into effect is illustrated by way of example, in which drawings:

10 Fig. 1 is a vertical section through combustion apparatus embodying the invention;

Fig. 2 is a section taken on the line 2—2 of Fig. 1; and

15 Fig. 3 is a section similar to Fig. 1 showing another form of apparatus.

18 Referring to Fig. 1, the apparatus illustrated shows the invention embodied in a cook stove of the heat accumulating magazine type but it will be understood that the invention is equally applicable to other specific forms of heating apparatus. In this figure the outer shell or casing of the stove is indicated at 10, the top plate of the stove being indicated at 12. A cylindrical metal member 14 acts as a fuel magazine and in the form shown is of heavy section to provide 25 heat storing capacity, the upper face of the member providing a hot plate for cooking purposes and being fitted with a central fuel charging opening closed by lid 16. The walls of an outer casing 18 surround the walls of the member 14 in spaced relation to provide an annular flue space 20 communicating with the offtake flue 22.

25 The bottom of the combustion space is formed by the grate indicated generally at 24 and provided, in the form shown, with a plurality of relatively narrow longitudinally extending grate bars 26. The bars 26 are spaced from each other so that the total area of the spaces formed between the bars is at least twice and preferably 30 three or more times as large as the total part of the grate area occupied by the grate bars. Advantageously, the grate is made from a material having poor heat conducting characteristics such for example as an alloy of iron and chromium.

35 When the grate is made of such material, chilling of the fuel particles lying closest to the grate bars due to conduction of heat therefrom by the grate bars is reduced. In order further to reduce conduction of heat from the fuel bed through the 40 grate structure, the grate is advantageously supported by means of narrow projections 28, having small contact areas, resting on ledges 30 projecting from the walls 32 forming the ashpit 34. In the embodiment illustrated, the ashpit walls 45 are made integral with walls 18.

45 In the apparatus illustrated, the combustion chamber is restricted at a relatively short distance above the grate 24, such restriction being formed by the inwardly projecting portions 36 of the outer casing wall structure.

50 Combustion air is admitted to the ashpit 34 through the inlet opening 38, which is in communication with an air inlet passage 40. Flow of air through opening 38 is controlled by a thermostatically actuated valve 42 which is advantageously responsive to variations in temperature of that which it is desired to heat by means of the fire. Both the ashpit and the combustion chamber are surrounded by heat insulating material 44 to prevent loss of heat. In Fig. 2 the outer shell and insulation have been omitted from the showing as well as the door for closing the opening 46 for removing ashes from the pit.

55 The combustion air entering the ashpit through opening 38 is preheated to a high degree in the

pit before reaching the grate and fuel bed, mostly by conduction and convection of heat from the ashpit walls which are heated to a high degree by radiation from the incandescent fuel bed immediately overlying the grate. The temperature of the ashpit walls is very high, owing to the fact that these walls are exposed to intense radiation of heat from the fire and are insulated against external loss of heat by the surrounding insulation.

60 In order to obtain effective radiation of heat to the side walls of the ashpit as well as to the bottom, the grate is advantageously bulged downwardly as shown in Fig. 1, thus making a so-called "hanging" grate. Heat may also be transmitted to the ashpit walls by conduction from the heated walls of the combustion chamber, with which they may be made integral as in Fig. 1 or arranged in some other suitable heat conducting relation.

65 Owing to the preheating of the combustion air before it reaches the fuel bed, a high rate of combustion will be developed as soon as the air strikes the fuel in the layer lying immediately on the grate and ash released as a result of this combustion will fall through the grate without necessity for the grate to be shaken.

70 If combustion should extend so as to take place in higher portions of the fuel column, the removal of the ash thereby released is more difficult since such ash is prevented from falling freely from the fuel bed by the underlying unconsumed fuel. It is therefore desirable that the layer in which active combustion takes place shall be as thin as possible. A high degree of preheating of the combustion air attains this object since with highly preheated air, the rapid combustion occurring in the lowermost layer of the fuel bed acts to rapidly consume the oxygen content of the air, so that little if any oxygen is available for combustion in 75 the portions above the lowermost layer.

75 Limitation of the height of the layer in which active combustion can take place is also contributed to by shaping the combustion chamber as shown in Fig. 1. As will be observed from the figure, the combustion gases leave the fuel bed laterally and escape into the flue space 20 at a distance not far above the grate. Consequently, such gases, which are very hot, cannot operate to raise the temperature of the upper 80 portions of the fuel bed to the ignition point. The interposition of the heavy heat absorbing member 14 between the passage 20 and the upper portions of the fuel stored in the magazine also tends to assist in maintaining the upper portion of the 85 stored fuel below ignition temperature.

85 It is of substantial importance that heat shall not be carried away from the burning fuel nearest the grate at too great a rate. If the fuel nearest the grate is cooled by conduction or radiation of heat therefrom, at too great a rate, it may be cooled below ignition temperature and remain in unburned or partially unburned state on the grate, thus preventing the free dislodgement and fall of the ash that is released by combustion of 90 the fuel. Accordingly, the grate is therefore arranged with relatively small heat conducting areas, that is, with relatively thin grate bars which in addition to having small heat conducting area, are preferably made from an alloy such as one of chromium and iron having a relatively low coefficient of heat conductivity. Also, in order to reduce conduction of heat from the grate, the area of contact between the grate and the ashpit walls is advantageously made small by supporting

the grate on projections of small area such as are indicated at 28.

In order to prevent pieces of fuel which are located along the edges of the grate from being unduly cooled by the walls of the combustion space, these walls are constricted immediately above the grate as by means of a flange 36 or the like so that fuel at the grate level does not come into contact with the side walls of the combustion chamber but is on the other hand maintained in appreciably spaced relation with respect thereto.

On the other hand, if conduction of heat from the fuel is too low, the temperature in the combustion zone may rise to such high level that the ash will fuse and form clinkers, thus preventing the free fall of the ash to the ashpit. Such condition may be prevented by proper proportioning of the elements making up the apparatus, which proportioning will vary in specific instances, depending upon the size and capacity of the apparatus and the nature of the specific fuel to be employed, that is, whether having ash of relatively low fusing temperature or relatively high fusing temperature. It will be understood by those skilled in the art that for specific cases, the maximum temperature to be attained in the combustion zone can be controlled by proportioning the structure in accordance with well known laws governing the rate of heat dissipation by radiation and convection.

In Fig. 3 there is illustrated another embodiment of the invention. In this figure the bottom and side walls of the ashpit are exposed to radiation from the incandescent fuel and heat may also be conducted thereto by conduction from the upper combustion chamber walls.

In this instance the air admission channel 40a, to which a controlled supply of air is admitted through the valve 42, embraces the ashpit, air being admitted to the latter through the openings 38a.

In order to assist in preheating the air flowing

through passage 40a, the ashpit walls may be advantageously provided with flanges 48 providing extended heat exchange surface.

In other respects, the embodiment shown in Fig. 3 is in general similar to that illustrated in Fig. 1, although in the present instance the constriction above the grate is formed by an inward sweep of the walls at 36a rather than by the inwardly extending flange as shown in Fig. 1.

It will be evident that the invention is not limited to the above described embodiments which have been shown by way of illustration only, but may be varied widely with respect to the form and shape of the several elements and the specific manner in which the preheating of the air is accomplished.

While the invention is not limited to any specific forms of solid fuels, it is primarily intended for and particularly applicable to the combustion of relatively non-volatile fuels such as anthracite, coke, or charcoal.

What I claim is:

Apparatus for continuous combustion of solid fuel including casing structure providing a combustion space and an ashpit below said combustion space, a grate for supporting fuel above said ashpit and means for supplying combustion air to said ashpit, said grate being made of material having a relatively low coefficient of heat conductivity and having supporting contact of relatively small area with said casing structure, whereby to minimize conduction of heat through the grate from the overlying fuel bed, said grate being proportioned so that the portion of the total grate area occupied by the grate bars is not more than one-half of the portion of the total grate area formed by the spaces between the grate bars, whereby to provide a relatively high rate of heat radiation downwardly through the grate to heat the walls of said ashpit and the combustion air admitted thereto before said air reaches the fuel bed.

GUNNAR GANNER.
